US0D1083849S

(12) **United States Design Patent** (10) **Patent No.:** **US D1,083,849 S**
Huang et al. (45) **Date of Patent:** **** Jul. 15, 2025**

(54) **ELECTRIC BLANKET CONTROLLER**

(71) Applicants: **Yuyao Fuyun Electronic Technology Co., Ltd.**, Yuyao (CN); **Fugui Huang**, Yongcheng (CN)

(72) Inventors: **Fugui Huang**, Yongcheng (CN); **Long Huang**, Yongcheng (CN)

(73) Assignees: **Yuyao Fuyun Electronic Technology Co., Ltd.**, Yuyao (CN); **Fugui Huang**, Yongcheng (CN)

(**) Term: **15 Years**

(21) Appl. No.: **29/983,210**

(22) Filed: **Jan. 9, 2025**

(51) LOC (15) Cl. **14-03**

(52) U.S. Cl.

(57) **CLAIM**

The ornamental design for an electric blanket controller, as shown and described.

DESCRIPTION

FIG. 1 is a front perspective view of an electric blanket controller, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the electric blanket controller, which form no part of the claimed design.

1 Claim, 8 Drawing Sheets
